UNITED STATES PATENT OFFICE.

THOMAS A. JENKINS, OF JERSEY CITY, NEW JERSEY.

SURFACING CONTAINER FOR TRACING CLOTH.

Application filed August 5, 1921. Serial No. 490,189.

To all whom it may concern:

Be it known that I, THOMAS A. JENKINS, a citizen of the United States, residing at Jersey City, in the county of Hudson and State of New Jersey, have invented certain new and useful Improvements in Surfacing Containers for Tracing Cloth, of which the following is a specification.

This invention relates to improvements in surfacing devices for tracing cloth and more particularly to a novel and improved powder dispensing container for use by draftsmen for preparing the surface of tracing cloth to receive ink.

15 The primary object of the invention is to provide a receptacle or container for uniformly dispensing a specially prepared powder by sifting the same on a tracing cloth and then treating the surface of the cloth by applying the powder to the same to remove any excess grease or moisture adhering thereto whereby the cloth will more readily take the ink.

It has been the practice when sprinkling 25 or otherwise arbitrarily sifting and applying a powder, such as prepared chalk and the like to smooth the surface of tracing cloth and to clean it of grease and moisture adhering thereto, by rubbing the powder over 30 the surface of the cloth with the hand or with a rag or the like, and then removing the excess powder after the cloth has been treated but the objection to this practice resides in the fact that the powder is not 35 evenly or uniformly distributed over the entire surface, thus leaving parts of the glazed cloth unprepared which do not readily take the ink. In addition there is great waste of the powder used without full 40 and complete results, and the excess powder has a tendency to adhere to the clothing of the user by being blown or dusted from the cloth being treated.

One of the objects of the invention therefore is to produce a novel and improved holder or receptacle wherein the body is formed of two telescopic frictionally engaged members, one of said members having a meshed fabric disposed over a false bottom 50 permitting the powder to be sifted, and the other member is provided with a fibrous material, such as felt or the like for applying the sifted powder evenly over the surface of the cloth for treatment.

55 Another and very important object of the invention is the provision of a sifting con-

tainer particularly adapted for use by draftsmen for preparing tracing cloth, and one in which the parts are extremely simple in construction, easily assembled, rigid and durable, highly efficient in operation, practical and capable of being manufactured at a very low cost whereby its commercial possibilities are greatly enhanced.

The invention will be best understood 65 from a consideration of the following detailed description taken in accordance with the accompanying drawing forming a part of this specification, with the understanding however, that the invention is not confined 70 to any strict conformity with the showing in the drawing, but may be changed and modified as long as such changes and modifications mark no material departure from the salient features of the invention as expressed 75 in the appended claim.

I attain these objects and others in the accompanying drawings, wherein:—

Figure 1 is an elevation showing the top 80 of the reservoir or container.

Figure 2 is an elevation showing the bottom thereof.

Figure 3 is a longitudinal sectional view taken therethrough.

Referring now to the drawings wherein like parts designate corresponding parts throughout the several views, Figure 1 designates a substantially rectangular receptacle or container the top of which is provided with a felt pad 2 or the like of any fibrous material to be used for applying the sifted powder over the tracing cloth. The rectangular member 1 is adapted to frictionally receive an inner, telescopic member 5 provided with a false bottom 4 and attached 90 to the respective ends of the inner section and stretched across and over the false bottom 4. I have provided a meshed piece of fabric or screening material 3 through which the powder may be sifted onto the 100 cloth to be treated. A cushion designated 6 is secured in any well known manner to the bottom portion of the inner section 5 so that the container may be more readily drawn over the tracing cloth to be treated 105 when sifting and spreading the powder thereon.

It will be readily observed that the telescopic, frictionally engaged inner and outer members may be readily separated for receiving a quantity of the prepared powder in which instance of course the container is 110

reversed, bottom side up, and the inner section 5 slid into the body portion of the outer section. In actual use, to those skilled in the art it will be apparent that by simply shaking powder over the tracing cloth, the proper quantity of powder will fall through the fabric, and then reversing the receptacle the said powder may be more evenly spread and rubbed into the cloth by the felt pad 2 10 so that the powder will absorb any moisture and clean the cloth of grease or any foreign matter adhering thereto.

In the accompanying drawings, I have illustrated my invention embodying in one 15 form by way of example, and which in practice has been found to be highly satisfactory in obtaining the desired results. It will be obvious however that other embodiments may be adopted, and that various changes 20 in the details of construction may be resorted to by those skilled in the art without departing from the spirit and scope of the invention. It is furthermore understood

that the invention is not necessarily limited or restricted to the precise elements shown 25 except in so far as such limitations are specified in the subject matter being claimed.

Having shown and described my invention what I now claim as new and desire to secure by Letters Patent of the United States, is:—

A receptacle of the class described comprising two interfitting substantially rectangular members having a false bottom, a cushion secured to the inner member adjacent the edges of the false bottom, a screening fabric covering the outer ends of the inner member and disposed over the cushion and said false bottom and a felt pad or rubbing surface on the top of the outer section 40 for applying sifted powder to a tracing cloth.

In testimony whereof, I affix my signature hereto.

THOMAS A. JENKINS.
